UNITED STATES PATENT OFFICE.

JOHN S. JULINE, OF DES MOINES, IOWA.

TOILET-PAPER HOLDER AND CUTTER.

1,005,228.

Specification of Letters Patent. Patented Oct. 10, 1911.

Application filed February 21, 1911. Serial No. 610,014.

To all whom it may concern:

Be it known that I, JOHN S. JULINE, a citizen of the United States, residing at Des Moines, in the county of Polk and State of Iowa, have invented a new and useful Improvement in Toilet-Paper Holders and Cutters, of which the following is a specification.

The object of my invention is to provide a device of this class of simple, durable and inexpensive construction.

A further object of my invention is to provide a device of this class with means combined with a single feed roller for cutting paper from a continuous roll of paper in one complete rotation of said feed roller, and means combined with said feed roller for cutting an opening substantially in the center of the portion or section of the paper cut as the feed roller is rotated.

The above and other objects and advantages of my invention will become apparent from the detailed description of the accompanying drawings in which—

Figure 1 is a front elevational view of a device made in accordance with my invention, the front of the case being removed to expose the interior parts, the removal to the front side being substantially on the line 1—1 of Fig. 2. Fig. 2 is a sectional end elevation of the same taken substantially on the line 2—2 of Fig. 1. Fig. 3 is a detailed elevation of the feed roller showing the side on which the blades are mounted for cutting the opening in the paper, Fig. 4 is a detailed elevation of the feed roller showing the opposite side to that shown in Fig. 3, and on which the blade for cutting the paper from the roll is mounted, Fig. 5 is a detached view of the stationary blade, Fig. 6 is a sectional end elevation of the stationary blade taken substantially on the line 3—3 of Fig. 5, Fig. 7 is a cross-sectional view of the blades mounted on the feed roller, Fig. 8 shows a modification arranged to cut the paper from the roll and the opening therein as the paper is fed from the roll in a folded sheet, Fig. 9 shows the paper as it is discharged after being cut, Fig. 10 shows the paper in Fig. 9 after it is folded outwardly.

Referring to the drawings in detail I have used the reference numeral 10 to designate the inclosing case which may be of any suitable form and material, and may be provided with suitable molding or otherwise

ornamented. The back portion 11 of the case is preferably made removable by means of detachable fasteners, such as screws, to allow access to the interior of the case, for any purpose such as inserting the roll of paper 12. The roll of paper 12 is mounted on the roll 13 which is rotatably mounted in the sides 14 and 15 of the case by any suitable means. The feed roller 16 is rotatably mounted in the sides 14 and 15 of the case preferably below the roll 13.

The blades 18 for cutting the opening in the paper, as best shown in Figs. 1 and 3, are constructed of steel, which is L-shaped in cross-section, and are mounted on the periphery of the feed roller 16 by means of bolts or screws 19 inserted through the openings in the base 20 of the blades. The upright portions of the blades are provided with a sharp edge 21 for cutting the opening in the paper by coöperating with a stationary blade presently to be described. The blades 18 are mounted on the feed roller at an angle to the axis of the feed roller and at an angle to each other substantially in a diamond shaped form, having a space 22 between the ends 23 and 24 of the blades 18 so that in cutting the opening in the paper, the portion cut away will not be entirely severed from the paper. The cutting blade for cutting the opening may be cast in one piece in a cylindrical form, therefore, I do not wish to limit myself to the specific form shown.

The blade 25 for cutting the paper from the roll is constructed of steel and cast in one piece which is L-shaped in cross-section, as best shown in Figs. 4 and 7. The base 26 of the blade 25 is provided with openings for inserting a bolt or screw 27 for mounting the blade on the periphery of the feed roller 16. The upright portion of the blade 25 is provided with a sharp edge 28, as best shown in Fig. 7, which serves as a cutting edge for cutting the paper from the roll which coöperates with the stationary blade presently to be described. The blade 25 is cast in one piece and is so formed that its cutting edges are set at an angle to the axis of the feed roller. The blade 25 is mounted on the feed roller diametrically opposite to the point 29 on the side on which the blades 18 are mounted. It is essential that the cutting edges of the blades 18 and 25 be set at an angle to the axis of the feed roller in order that the feed roller may have

an opportunity to feed the paper while it is being cut.

A stationary blade 30 is rigidly secured to the side 11 of the case, preferably in a plane parallel with the axis of the feed roller 16, by any suitable means, such as the L-irons 31 and the bolts 32 and 33, and is so positioned as to coöperate with the blades 18 for cutting the opening in the paper and with the 10 blade 25 to sever the paper from the roll as the feed roller is rotated. The spring members 34 and 35 are secured to the top of the case 10 by means of bolts 36 and are so formed when in position to engage the paper on the roll 12 and to impart a yielding pressure upon said roll, thus holding the paper intact on the roll 12. The feed roller 16 is covered on its surface at either end, with sand paper 37 or similar material for im- 20 parting to said roll a rough surface for properly engaging the paper when said roller is being rotated. The spring member 38 is rigidly secured to the back portion 11 of the case 10, at either end, and under the sta- 25 tionary blade 30 by any suitable means, such as the bolts 39, and are so formed and positioned as to engage the paper on the feed roller 16, thus imparting a yielding pressure on said roll to hold the paper intact. A 30 crank handle 40 is rigidly secured to the feed roller 16, by any suitable means, for rotat- ing the same.

It will be seen that the paper used in this device must be of sufficient width to fit the 35 ordinary stool in water closets, therefore, in the form of my invention shown and described in Figs. 1, 2, 3, 4, 5, 6 and 7, I have shown and described a device so designed as to cut the paper from the roll and an open- 40 ing therein as the paper is fed from the roll in a single sheet. In Figs. 8, 9 and 10 my toilet paper holder and cutter is shown in a form designed to be used in places where it is desired or is necessary to economize space, 45 as for instance, Pullman cars and the like, and it is designed to cut the paper from the roll and an opening therein as the paper is fed from said roll folded laterally upon itself or in a double sheet. In these figures 50 the roll of paper is made of paper of sufficient width to fit the ordinary stool in wa- ter closets, which is folded laterally intermediate of its edges upon itself, thus forming a double sheet roll of one half the width 55 of a single sheet roll made up of the same width paper. As in Fig. 1 the roll of paper is mounted on the roll 13 which is rotatably mounted in the sides 14 and 15. The blade 18 for cutting the opening in the paper is 60 made of steel, which is L-shaped in cross section, and which is cast in one piece in a semi-cylindrical form and is mounted on one side of the feed roller 16 near one end thereof, by any suitable means, such as 65 screws 19, and having its outer edges 18^A and

18^B in vertical alinement with the edge of said feed roller, as shown in Fig. 8. The roll of paper 12 is mounted on the roll so that the folded edge 12^A of the paper will correspond with the edges 18^A and 18^B of the blade 18. A cutting blade is mounted on the feed roller 16 diametrically opposite the point 29 of said feed roller similar to the blade 25 in Figs. 2 and 4. A stationary blade is rigidly secured to the side of the case preferably in a plane parallel with the axis of the feed roller 16 similar to the blade 30 in Figs. 2 and 5. As the feed roller is rotated the semi-cylindrical blade 18 co- 70 operates with the stationary blade thereby cutting the opening in the paper and as the feed roller is rotated, the cutting blade 25 coöperates with the stationary blade 30 thereby cutting the paper from the roll. 75

The paper is fed from the roll down- 80 wardly under the feed roller and out the discharge opening as the feed roller is rotated and is discharged at the discharge opening in a folded position having a cut away portion 13^A from one of its sides, as 85 shown in Fig. 9. After the paper has been cut and passed out the discharge opening as above described and it is desired to use the same, the paper is then folded outwardly and will be in the form shown in Fig. 10 90 having an opening 13^B substantially in its center. 95

14^A designates the line on which the paper is folded as shown in Fig. 9.

In practical operation and assuming that 100 the parts are assembled as herein shown and described, a roll of paper is mounted on the roll 13 and the paper is then passed downwardly between the feed roller 16 and the stationary cutting blade 30, thence down- 105 wardly under the feed roller 16 and between the spring member 38, thence downwardly through the discharge opening 41. When it is desired to turn out a supply of paper, the crank handle 40 is turned from right to left, 110 thus rotating the feed roller 16. The blades 18 first cut the opening in the paper by co- 115 operating with the stationary cutting blade 30 and the blade 25 cuts the paper from the roll by coöperating with the stationary blade 30 as the feed roller is rotated, thus turning out a supply of paper having an opening substantially in its center.

Having thus described my invention what I claim as new and desire to secure by Letters Patent of the United States is:

1. In a toilet paper holder and cutter, a case having a discharge opening, a roll of paper and a feed roller mounted in said case, a stationary cutting blade mounted in a position parallel with the axis of said feed roller, a blade on said feed roller adapted to coöperate with said stationary cutting blade for cutting an opening in said paper opening, a roll of paper and a feed roller 125

for cutting the paper from said roll, and means for rotating said roller.

2. A toilet paper holder and cutter, comprising an inclosing case having a discharge opening, a roll of paper and a feed roller rotatably mounted in said case, a stationary cutting blade mounted in a position in said case parallel with the axis of said feed roller, a cutting blade mounted on the surface of said feed roller and adapted to coöperate with said stationary blade in cutting the paper from said roll and a second blade mounted on said roller diametrically opposite said cutting blade to cut an opening substantially in the center of each portion cut from said roll, and means for rotating said feed roller substantially as and for the purpose described.

3. In a toilet paper holder and cutter, an inclosing case having a discharge opening, a roll of paper and a feed roller rotatably mounted therein, a stationary cutting blade mounted in said case a cutter of zigzag form carried on said roller adapted to co-operate with said stationary blade for cutting the paper from the roll and a second blade mounted on said roller diametrically opposite said zigzag blade and adapted to cut an opening substantially in the center of each portion cut from the roll.

4. A toilet paper holder and cutter, comprising an inclosing case having a discharge opening, a roll of paper and a feed roller rotatably mounted in said case, a stationary cutting blade mounted in a position in said case parallel with the axis of said feed roller, cutting blades mounted on one side of said roll at an angle to the axis of said feed roller, in substantially a diamond-shaped form, for cutting an opening in said paper, a cutting blade for cutting the paper from the roll mounted on said feed roller diametrically opposite the blades for cutting the opening, having its cutting edges set at an angle to the axis of said feed roller, and means for rotating said feed roller substantially as and for the purpose described.

5. A toilet paper holder and cutter, comprising an inclosing case having a discharge opening, a roll of paper and a feed roller rotatably mounted in said case, a stationary cutting blade mounted in a position in said case parallel with the axis of said feed roller, a cutting blade mounted on the surface of said feed roller having its cutting edges set at an angle to the axis of said feed roller and adapted to coöperate with the stationary cutting blade to cut the paper from the roll, cutting blades mounted on the surface of said feed roller diametrically opposite to the blade for cutting the paper from the roll and set at an angle to the axis of said feed roller and to each other in sub-

stantially a diamond-shaped form and adapted to coöperate with the stationary cutting blade for cutting an opening in the paper as the feed roller is rotated, and means for rotating said feed roller substantially as and for the purpose described.

6. In a toilet paper holder and cutter, a case having a discharge opening, a roll of paper having the paper folded laterally upon itself rotatably mounted therein, a feed roller mounted in said case, a stationary cutting blade mounted in a position parallel with the axis of said feed roller, and means on said feed roller adapted to co-operate with said stationary cutting blade for cutting an opening in said paper and for cutting the paper from said roll, and means for rotating said roll substantially as and for the purpose described.

7. A toilet paper holder and cutter, comprising an inclosing case having a discharge opening, a roll of paper consisting of paper laterally folded upon itself, a feed roller mounted in said case, a stationary cutting blade mounted in a position parallel with the axis of said feed roller, a semi-cylindrical cutting blade mounted on the side and near one end of said roll adapted to co-operate with said stationary blade for cutting an opening in said paper, a cutting blade mounted on one side of said roll adapted to coöperate with said stationary blade for cutting the paper from said roll, and means for rotating said feed roller substantially as and for the purpose described.

8. A toilet paper holder and cutter, comprising an inclosing case having a discharge opening, a roll of paper having the paper folded laterally upon itself rotatably mounted in said case, a feed roller mounted in said case, a stationary cutting blade mounted in a position in said case parallel with the axis of said feed roller, a cutting blade mounted on the surface of said feed roller having its cutting edges set at an angle to the axis of said feed roller and adapted to coöperate with said stationary cutting blade for cutting the paper from the roll, a semi-cylindrical cutting blade mounted on one side of and near one end of said roll adapted to coöperate with said stationary cutting blade for cutting the opening in the paper as the feed roller is rotated, and means for rotating said feed roller substantially as and for the purpose described.

In witness whereof, I hereunto subscribe my name this 11th day of February, A. D., 1911.

JOHN S. JULINE.
